UNITED STATES PATENT OFFICE.

LEOPOLD TROPP, OF BROOKLYN, AND BERT RIVKIN, OF NEW YORK, N. Y., ASSIGNEES
TO SECURITY VEHICLE LOCK & BRAKE CO., INC., A CORPORATION OF NEW YORK.

LOCK FOR VEHICLES.

1,201,391.

Specification of Letters Patent. Patented Oct. 17, 1916.

Original application filed February 25, 1915, Serial No. 10,515. Divided and this application filed September 17, 1915. Serial No. 51,243.

To all whom it may concern:

Be it known that we, LEOPOLD TROPP and BERT RIVKIN, citizens of the United States, and residents, respectively, of Brooklyn, in the county of Kings, and New York, in the county of Bronx, and State of New York, have invented certain new and useful Improvements in Locks for Vehicles, of which the following is a specification.

10 This invention relates to improvements in locks, and more especially to locks for vehicles, and is a divisional application of an application filed by us on February 25, 1915, Serial No. 10,515.

15 The object of this invention is to provide a lock of this class which is simple in construction and easy to assemble and to secure to the vehicle.

20 The further object is to provide a device of this kind in which a standard lock can be used, and when a driver is discharged a new lock can be substituted for the old lock.

25 The still further objects will appear from a detailed description of the invention, which consists in the features of construction and combination of parts hereinafter described and claimed and shown in the illustrations, of which—

30 Figure 1 is an elevation of the casing containing the spring actuated locking mechanism and having the front plate removed and showing the mechanism in full lines in the locked position and in dotted lines in the open position; Fig. 2 is a side elevation, 35 partly broken away and showing almost a central sectional view of the casing; Fig. 3 is a perspective view of the casing; Fig. 4 is a side elevation of a wagon partly broken away to show one way in which the locking 40 mechanism may be used; Fig. 5 is a plan view of the mechanism shown in Fig. 4, and is shown in order more clearly to illustrate how the lock can be used.

45 While we have only shown one construction of our device, it will be understood that many changes and modifications and mechanical equivalents may be substituted for the various parts of our invention without departing from the spirit of our invention, and it is not thought necessary to illustrate the modifications, as they are obvious to those skilled in the art.

50 Referring to Figs. 1 to 3, it will be seen that we provide a suitable casing 1 formed

of two parts, and for convenience we will 55 designate them as the front portion or part 2 and the back portion or part 3. The back portion is formed with a flange 4, the outer portion or edge fitting the inside of the front portion 2, which is formed by the sides 60 5 of the front portion. The parts 2 and 3 are held together by the bolts 6, which also secure the lock to the vehicle, but if desired other means may be used to secure the parts 65 together independently of the bolts 6. The 70 part 3 is provided with studs 7 located in bosses 8, and located upon the studs 7 are two spring actuated arms 9 which are held in their locked position by the spring 10, which causes their locking faces 11 to bear 75 against the rod 12, which carries the locking member 13 located in the chamber 14 of the extension 15 of the part 3, and the rear end of the extension forms a bearing 16 for the rod 12, which has its forward bearing 17 in the extension 18 of the part 2, and within the extension 18 is a chamber 19 for the reception of the locking member 13. Located in the bore 20 is a stud 21, and located on the stud is a double face cam 22, 80 having cams 23 and 24 which act against the faces 25 and 26 of the arms 9 to throw them open to release the locking member 13. The cam 22 is under the control of the lock 27, which is of a standard make and suitably 85 secured in the extension 28 and has its tumbler barrel in register with the stud 21 and its operating link 29 extending into the rectangular opening 30 of the cam 22.

90 Referring to Figs. 4 and 5, in which we have shown just enough of the mechanism to illustrate one of the methods of using our lock, and it is not thought necessary to go into the details thereof, but it will 95 be seen that the vehicle is provided with a foot lever 31 suitably secured to the wagon and having a link 32 connecting it to the operating rod 33, which throws the plungers 34 out between the spokes of the wheels to lock them from turning, and the plungers 100 34 are withdrawn by the mechanism in the casing 35 when the rod 33 is released. The rod 33 is connected to the rod 12 by the coupling 36, so that it will be seen that the rod 33 is controlled by the rod 12 and therefore the rod 12 controls the entire mechanism.

105 The operation of this device is very sim-

ple. When the driver pushes the lever 31 forward, the link 32 causes the rods 33 and 12 to move forward and the mechanism in the casing 35 throws out the plungers 34 and at the same time the conical locking member 13 presses between the faces 11 of the links 9 and forces them apart and passes into the chamber 19, and the spring 10 causes the faces 11 to snap behind the locking member 13 and thus holds everything in its locked position. When it is desired to release the vehicle, the key is inserted into the lock and given a quarter of a turn, and the cam 22 turns, and the cams 23 and 24 acting against the faces 25 and 26 cause the arms 9 to swing apart and release the locking member 13, and the mechanism in the casing returns all the parts to their normal positions.

Having fully described our invention, it will be seen that we have accomplished the foregoing objects, and what we claim as our invention is:

1. The combination of a casing, inclosing a substantially flat chamber, a pair of arms pivoted in the casing to engage at their free ends, a spring connecting the arms to yieldably retain them in engagement, the arms having registering channels at their engaging portions, the casing also having opposite extensions at one end to form a transversely extending chamber into which the engaging ends of the arms project, a plunger slidable in the transverse chamber extending between the arms, a conical abutment on the plunger arranged to engage the arms to separate them and to be locked in advanced position by the arms, the casing having an extension at an intermediate portion to provide a cylindrical chamber, a lock of the pin-cylinder type mounted in said chamber, a cam controlled by said lock and

positioned between the arms to swing them apart on turning of the lock.

2. The combination of a casing, a pair of arms pivoted in the casing to engage at their free ends, a spring connecting the arms to yieldably retain the arms in engagement, the arms having registering channels at their engaging portions, a plunger extending into the casing and between the arms at said channels, the plunger being slidable in a path parallel with the axes of the arms, a conical abutment on the plunger arranged to engage and swing the arms when advanced, and to be retained by the arms in advanced position, a lock extending into the casing, and a cam operated by the lock and arranged to engage and swing the arms.

3. The combination of a casing, inclosing a substantially flat chamber, a pair of arms pivoted in the casing to engage at their free ends, the casing also having opposite extensions at one end to form a transversely extending chamber into which the engaging ends of the arms project, a plunger slidable in the transverse chamber and extending between the arms, an abutment on the plunger arranged to engage the arms to be locked in advanced position by the arms, the casing having an extension at an intermediate portion to provide a cylindrical chamber, a lock of the pin-cylinder type mounted in said chamber, and a cam controlled by said lock and positioned between the arms to swing them apart on turning of the lock.

Signed at New York, in the county of New York and State of New York, this 4th day of September, A. D. 1915.

LEOPOLD TROPP.
BERT RIVKIN.
